FORM FOR MOLDING CONCRETE
STRUCTURES

Lawrence T. Thorn, Memphis, Tenn.

Application October 16, 1933, Serial No. 693,805

10 Claims. (Cl. 25—118)

This invention relates to forms and methods for forming concrete structures and is particularly directed to such means for, and methods of, constructing elongated structures of varying dimensions and patterns, such for instance as the 5 guard rails of concrete bridges, which structures require careful adjustment to preserve accurate alignment longitudinally, to adjust for vertical lines on grades and to adjust for varying spacing 10 of parts incident to variations in span length or the like.

In building concrete bridges, more and more attention is being paid to the design, alignment and finish of the guard rails lying at the side 15 edges of the structure. At the ends of the bridge, posts are placed and in structures of any considerable length the intermediate space between these posts is divided into panels marked off by additional posts and at times by sub-posts 20 of lesser size. Lying along the surface of the bridge between these posts, and usually either integral with or securely attached to the floor surface of the bridge, are longitudinal beams constituting wheel guards and spaced above these 25 lower beams are beams usually designated hand rails. It is of extreme importance in a structure intended to be permanent as these concrete 30 bridges are, that these rails be accurately aligned longitudinally and this is particularly true of the top rail, the alignment of which intrudes itself upon the vision of the users of the bridge, as they approach and cross. The space between the upper 35 and lower rails is paneled, in most cases this being effected by small posts or spindles spaced apart and great care must be taken that these spindles are vertically disposed whether the bridge be level or on a grade.

Many variations also are necessary or desirable in the rail dimensions, height, size and spacing 40 of the spindles.

The objects of the present invention are:—

To provide means for economically forming or molding these guard rails in a finished and workmanlike manner;

To provide means for accomplishing the longitudinal alignment of the rails forming part of these guards;

To provide means for securely, efficiently, and adjustably securing the mold parts together;

To provide means for adjusting the dimensions 50 of the rails;

To provide means for varying the spacing of the upper or hand rail from the lower or wheel rail;

To provide means for varying the dimension 55 and spacing of the spindles;

To provide means for vertically aligning the spindles; and

To provide such a mold structure which will be easily removable without destruction of the usually green and therefore insufficiently hardened concrete.

The means by which the foregoing and other objects are accomplished and the manner of their accomplishment will readily be seen from the following specification by reference to the 10 accompanying drawings, in which:—

Fig. 1 is a vertical sectional elevation of the forms with concrete in place, taken as on the line I—I of Fig. 3, and on a substantially larger scale than Fig. 3.

Fig. 1A is a much enlarged fragmentary detail showing attachment of a stringer to a stud.

Fig. 2 is a fragmentary sectional elevation taken as on the line II—II of Fig. 3 and on the same scale as Fig. 1.

Fig. 3 is a side elevation of the forms, a portion of the panel being broken away, and a fragmentary portion of a second panel being shown in section taken substantially along the longitudinal center line.

Fig. 4 is a sectional elevation of a fragmentary portion of one of the side forms adjacent to and including a sub-post portion.

Fig. 5 is a horizontal section taken as on the line V—V of Fig. 4 with two opposed forms shown 30 assembled.

Fig. 6 is a fragmentary vertical section taken as on the line VI—VI of Fig. 5.

Fig. 7 is a fragmentary sectional elevation, taken as on the longitudinal center line of the 35 forms, of a modified form of spindle forming molds for a panel, a portion of the panel being broken away.

Figs. 8 and 9 are vertical sectional elevations of fragmentary portions of a panel similar to Fig. 40 7, showing modifications of the spindle design.

Fig. 10 is a fragmentary horizontal section taken as on the line X—X of Fig. 7.

Fig. 11 is a fragmentary vertical section on an enlarged scale of the lower end of one of the 45 spindle molds shown in Fig. 7.

Fig. 12 is a fragmentary sectional elevation, on an enlarged scale taken as on the line I—I of Fig. 3, showing a modification of the means for 50 adjusting at a sub-post.

Fig. 13 is a fragmentary section of a portion of one of the form members taken as on the line XIII—XIII of Fig. 12.

Fig. 14 is a fragmentary sectional plan taken 55

as on the line XIV—XIV of Figs. 15 and 16 with a locking key in place.

Fig. 15 is a fragmentary portion of one of the form members on an enlarged scale showing the conformation of the slot therein.

Fig. 16 is a fragmentary sectional elevation taken as on the line XVI—XVI of Fig. 14 showing the locking key and securing wedge in place.

Fig. 17 is a face view of an end plate on the same scale as Fig. 1 taken as on the line XVII—XVII of Figs. 3 and 19.

Fig. 18 is a plan view of the same plate.

Fig. 19 is a vertical elevation thereof.

Referring now to the drawings in which the various parts are indicated by numerals, the form is made up of two, usually identical, independent halves. Each of these halves has a frame structure comprising upper and lower longitudinal stringers 10 and 11 respectively, preferably of angle iron, the lower of which stringers 11 is rigidly secured to a number of vertically disposed studs 12, preferably as by welding. These studs usually of channel iron preferably are uniformly spaced throughout the length of the frame except that where a frame covers more than one panel, a variation in spacing often occurs at the sub-post. The stringer 10 is provided adjacent each stud with a bracket 13, ordinarily short lengths of angle iron, which bracket is secured to the stringer preferably as by welding. Each stud is provided with a plurality of vertically disposed slots 14 and the brackets are provided with complementary slots 13A, whereby the brackets may be secured to the studs as by bolts 15, this method of attachment providing for vertical adjustment of the brackets and of the stringer to which they are attached. The stringer 10 may rest directly against the stud 12, in which case the leg portion 10A of the stringer will be at right angles to the stud, and horizontal, but it is preferable, as shown in Fig. 1A, to place between the stringer and the stud a wedge shaped filler 16, which may be secured to the stringer by welding and which will cause the leg portion 10A thereof to slope downwardly away from the stud, the purpose of such slope being to facilitate removal of the form from the concrete.

The upper ends of the struts 14 are preferably capped by a longitudinal member 17 and the lower ends rest on a similar longitudinal member or sill, 18, to both of which longitudinal members they are secured, preferably as by welding.

19 is a vertically disposed plate which extends substantially the length of the frame and is the side form for one side of the upper or hand rail 20.

Preferably the upper edge of the plate 19 is stiffened by a coextensive angle member 21, and its lower edge is stiffened by a channel shaped member 22, which extends inward toward the concrete should it be desired to form a rabbet of similar shape in the finished concrete. Secured to the plate 19, preferably as by welding, and spaced to conform to the spacing of the studs 12 are angle iron brackets 23. These brackets are provided with horizontally disposed slots 24 and the studs with complementary vertical slots 25, through which bolts, purposely, for the purpose of clearness not shown, may be passed to secure the brackets to the studs. The vertical slots in the studs permit vertical adjustment and the horizontal studs in the brackets permit horizontal alignment, both with respect to the frame. 26 is a member, preferably angle iron, which preferably extends continuously from end to end of

the frame and which is secured, preferably as by welding to the studs, forming an additional stiffener for the frame. Secured to this angle iron at suitable intervals, preferably by welding, are nuts 27 through which aligning screws 28, 5 for the bottom of the plate, pass. Secured, preferably to the underside of the cap 17, preferably by welding, are nuts 29 through which aligning screws 30, for the top of the plate, pass. Filler blocks 31 are used if necessary to bring the aligning screws below the flanges of the cap. 32 is a vertically disposed plate, coextensive with and also forming part of the frame, which is secured to the lower portion of the studs 12 as a side form for one side of the bottom rail 33. 15 The upper edges of these rails being ordinarily beveled, the upper portion 34 of the plate 32 is preferably bent inward on a corresponding bevel. 35 is an angle iron secured to the studs 12 and reinforcing the inwardly turned portion 34 of 20 the plate.

The form half thus constructed, comprises an integral frame having the form plate for the lower rail integrally attached and the form plate and other form members for the top rail ad- 25 justably secured. Two of these halves are aligned and spaced apart to constitute the main portions of the form for the guard of a bridge.

The vertical webs of the members 10 and 11 are provided, preferably at closely and equally 30 spaced intervals with slots 36, 37 respectively which are adapted to receive transverse tie bars 38, 39. These tie bars extend from slots in the members 10 and 11 of one side frame to slots in the corresponding members 10 and 11 of the 35 other side frame and are themselves provided with slots 40 adapted to receive locking keys 41, which keys engage against the outer surfaces of the members 10 and 11 to prevent the form from spreading apart, these keys being of usual taper 40 or wedge shape.

In Figs. 15, 16 and 17 a special form of slot 40A and of notched key 41A is shown, the enlarged portion of the slot being adapted to receive an ordinary wrought nail 42 as a tightening wedge. 45 The upper tie bars 38 also serve as supports for spacer blocks 43 and plates 44, supported by such blocks, which form the underside of the top rail between the spindles 45.

The ends of the concrete rails both top and 50 bottom may abut solidly against the main posts 46 (Fig. 3) used in connection therewith but usually at one end, if not at both ends, they are spaced therefrom to provide for expansion. In such case end plates 47, 48 are used to make the 55 end form for the rails. A typical plate 48 is shown in Figs. 17, 18 and 19. This plate has secured thereto a transverse strap 49 having ends 50 bent at right angles, which ends are adapted to be secured to the stringers 11 as by bolts 51. 60 Otherwise the plates may be braced from the posts 46 in any usual or desired manner.

Where sub-posts such as the post 20A, Fig. 1, occur, that is posts which do not require an enlargement of the rails, the frames extend con- 65 tinuously past such sub-posts. The sides of the posts in such case are formed of plates 52, each having an outwardly turned flange 53 at the bottom, which flange rests on the upper surface of the angle 35 and/or the inclined portion 34 of 70 the lower side plate 32, and an outwardly flanged portion 54 which underlies and closely abuts the horizontal leg of the frame member 10. 55 is a panel form of desired configuration secured to the plate 52.

This panel may be integrally secured, as by welding, or may be secured by bolts 56 such as shown in Fig. 5 which pass through slots 56A Fig. 5, allowing horizontal movement. Adjacent to the side edges of the plates 52, are end retaining strips 57 which are secured at their upper and lower ends as by bolts 58. These bolts pass through the strips 52 and through horizontally disposed slots 59 by means of which the upper and/or lower ends of each strip may be shifted to vertically position the strip, as for instance when the bridge and the railings are on a grade. Disposed between the plates 53 are removable end plates 60. Each of these end plates has secured to its side edges, as by welding, channel shaped members 61 having outwardly turned flanges 62, the groove lying between the flanges being adapted to receive the strip 57 whereby when the strips 57 are adjusted to a vertical position and the end plates 60 are disposed between the side plates 52 and engaged with the strips a completely closed column form is made. The groove in a standard channel being ordinarily flaring, the strips 52 are preferably also so shaped. Preferably the lower ends of the plates 60 are provided with outwardly turned flange portions 63, which flange portions extend substantially to the adjacent spindles and prevent upward flow of concrete in the lower rails at such place. Secured to, and projecting outward from, the plates 52 are bolts 64 which extend through the slots 36, 37 in the stringers 10 and 11 respectively. Each of these bolts is provided with nuts 65, 66 on opposite sides of these stringers by means of which bolts the plates are supported solidly with respect to such stringers, and also by means of which adjustment of these plates particularly at the upper ends thereof may be had relatively to the stringers.

It occurs at times that positioning of the bolts 65 and of the slots 36, 37 in the stringers 10 and 11 do not conform, in such case a modification shown in Figs. 12 and 13 is made use of. In this modification an angle iron 70 is secured to the plate 52, this angle iron having a vertically disposed slotted leg 71. Adjusting bolts 72 connect this angle with the stringer 11 (or 10 as the case may be), the slots in the legs 71 of the angle permitting attachment at any desired point.

If desired two or more frames may be clamped together to secure a desired length of frame. In such case the end stud 12 of one frame is abutted against the end stud 12 of a second frame, as shown in Fig. 14, and key 41A inserted in the slots 40A. The keys 41A are notched, as shown in Fig. 15, to engage the abutting webs of the studs and a suitable wedge, such as the nail 42, is driven in to wedge the web tightly in place and complete the engagement.

The foregoing description has been confined largely to forms for the construction of hand rails making use of precast spindles. In Figures 7 to 11 inclusive, forms are illustrated for pouring the rails and spindles integrally. In such case the side plates 52A of the sub-posts are substantially coextensive with the frames. Disposed between these side plates are removable form members each occupying the space between a pair of adjacent spindles. Each of these form members comprises a pair of vertically disposed plates 72, adapted to extend from one side plate 52A to the opposite one thereof. At the top these plates are connected by an integral plate, which may be a flat plate 73 as shown in Fig. 7, of gothic arch form 73A as shown in Fig. 8, two upwardly

extending plates 73B as shown in Fig. 9, or such other configuration as may be desired. The lower portion of each side plate 72 has a short section 74 hingedly connected thereto. The lower end 75 of each of these short sections is bent inward at right angles, the length of the inwardly bent portions being one-half the distance between the vertical portions. Complementary hasp and staple locking members 77 and 78 secured to the sections 75 are used to hold the sections in working position. If desired to bevel the edges of the spindles, suitably shaped and disposed blocks 79 are secured to the plates 52A. Also secured to the plates 52A are blocks 80 which are spaced from the blocks 79 to form grooves 81 adapted to receive the edges of the plates 72. Should the spindle edges not be beveled, positioning channels corresponding to the channels 61 Fig. 5 may be secured to the plates 72, in lieu of the blocks 80 and complementary strips, corresponding to the strips 59, be secured to the plates 52A.

In these types, opposed plates 52A are assembled with the above described form members or cores, therebetween, and are clamped together, by ties and wedges as before. To permit insertion of the ties the plates 52A, are provided with slots 36A lying within the cores and aligning with slots 36 in the stringers 10, 11.

In making use of the forms hereinbefore described for building the guard rails of concrete bridges, the bridge floor is completed, preferably leaving reinforcing rods projecting upward in usual and well known manner as anchorage for posts, sub-posts and rails. Preferably the main posts 46 at the ends of the bridge and such intermediate points as are necessary or desired are also constructed.

If precast spindles are to be used these spindles are cast in suitable forms and allowed to set and cure. In their preferred form these spindles are cast with laterally projecting flanges 90 at their top ends whereby to provide means for supporting them when placed. Also they may be, and preferably are, provided with upwardly and downwardly extending reinforcing rods 91 and 92 projecting respectively from their upper and lower ends.

The outer side frame, including the form plate 32 for the side of the wheel guard, the plate 19 for the side of the hand rail and plate 52 for intermediate sub-posts, is placed, but not finally positioned, between two of the end posts with the plates facing inward. The complementary frame for the inner side of the rail is then placed with the plates facing outward and is moved into position and secured and braced. It will be noted that the frame members 26 extend beyond the otherwise end of the frame and overlap the posts 46 whereby they may be, at least initially, of use in the positioning of the forms, that is they allow the outer frame to be initially braced against the outer side of the posts and prevent the inner frame from being pushed too far outward. Also they are of assistance in the alignment of the ends of the frame with respect to the posts.

The outer frame is roughly positioned and aligned and the spindles are then dropped into place with the flanges 90 thereof resting on the inwardly projecting portions 10A of the upper stringers. Ties 38 and 39 are then inserted and tightened up until the edges of the stringers 10 and 11 lightly engage and align the spindles. The top ends of the spindles are now adjusted to

secure uniform spacing and additional ties are placed one on each side of the spindle, such additional ties however not necessarily being utilized to clamp the frame together. The blocks 43 are placed on these ties and supported thereby between each and every spindle and on these blocks thin plates 44 are placed to provide a form for the underside of the concrete rail between the spindles. These thin plates 44 are used in addition to the blocks in order that the blocks may be removed while leaving the concrete protected by the thin plates. Preferably the thin plates are in two parts so as to allow their later removal from the concrete surface without disturbing the same. After properly spacing the spindles, the ties connecting the top stringers are additionally tightened to grip the spindles more firmly. The lower ends of the spindles are now moved, if it be necessary, to bring the spindles into vertical position and the ties connecting the lower stringers are tightened.

At the time the frames are brought into position the end plates for the sub-posts are placed and as the frames are brought together they are clamped there between. Prior to such clamping they are adjusted to a vertical position and where the panel form of the post is secured by bolts this also is adjusted so that its side edges may be vertical. The spindles having been properly positioned and vertically aligned, and the panel plates similarly aligned, final tightening of the ties is made to clamp the upper and lower stringers against the spindles and the end plates of the sub-posts. In accomplishing this tightening minor inequalities in alignment occur which inequalities so far as the top rail is concerned, are now corrected by adjusting the screws 28 and 30 respectively until the side plates 19 for the upper rail are definitely straight and true. In tightening the stringers against the spindles, it sometimes happens that the form plate 52 for the sub-post must be loosened to allow proper clamping against the spindles, or that they must be tightened to secure proper gripping against the end plates of the post and such adjustment may be accomplished by means of the adjusting bolts 64.

Where the spindles are to be cast integral with the top and bottom rails, the spindle cores are inserted between the side plates and clamping and aligning, accomplished as before.

It will be understood that clamping of the stringers through the medium of the ties 38 and 39 may be accomplished by means of the wedges described, or that such tightening may be accomplished by other usual and well-known forms of tightening device.

The forms having been properly clamped and aligned concrete is poured into the bottom rail until the same is level with the top of the members 35 and is struck off around and between the spindles, concrete is also poured into the top of the forms to fill the top rail and the sub-posts. Concrete so placed is leveled off and the top finish of the rail accomplished as by means of a strike board or screed 100, which conforms to the desired shape of the top of the rail. Where the spindles are cast integral with the rails all the concrete is poured into the forms from the top, the finishing of the top being similarly accomplished. In either event the guide for the strike board is ordinarily the top edge of the side forms 19 or the reinforcing angles 21 attached thereto.

After pouring, the concrete is allowed to set in

usual manner until it is sufficiently hardened to retain its shape, preferably however, the forms being removed while the concrete is sufficiently green to be touched up and finished. After such hardening the ties are loosened and the forms pulled laterally away from the rail. In such disengagement, the slope given the top stringer provides sufficient draft to allow such removal. Also since the top of the form is first pulled outward, the lower edges 53 of the sub-post panels 10 lift away and readily disengage from the concrete.

After removal of the side forms, where the spindles are cast integral with the rails, the cores remain in place and must be individually removed. To accomplish this the lower ends 75 of 15 the cores are disengaged and the parts 74—75 are swung inward to the positions 75X shown dotted in Fig. 11. The core sides are thus freed to move inward and be moved downward to complete the release of the core and allow its lateral removal. 20

After stripping, the railings and spindles are finished in usual or desired manner.

It will be understood that while the form plates 32 for the lower rail have been shown directly attached to the lower portion of the studs, they 25 may be provided with brackets corresponding to the brackets 23 of the upper plates 19 and with similar adjusting means whereby alignment of the lower plates relative to the frame structure may be accomplished.

Having described my invention what I claim is:

1. In a form for concrete, a form member comprising a frame which includes vertically disposed studs, a longitudinal stringer and a longitudinal 35 plate vertically disposed, rigidly attached to said studs, a second stringer disposed thereabove and adjustably attached to said studs, a longitudinally disposed form plate adjustably attached to said studs and having its lower edge contacting said 40 second stringer, and means for aligning said adjustable form plate with reference to the alignment of said frame.

2. In a form for concrete, a form member comprising a frame which includes vertically disposed 45 studs, a longitudinally disposed stringer, a longitudinally disposed sill member and a longitudinal 50 plate vertically disposed, rigidly attached to said studs, a second stringer disposed thereabove and adjustably attached to said studs, a longitudinal 55 form plate, vertically disposed, and adjustably attached to said studs, and means for aligning said adjustable form plate with reference to the alignment of said frame.

3. In a form for concrete, a form member comprising a frame which includes vertically disposed 55 studs, a longitudinally disposed stringer, a longitudinally disposed cap member, and a longitudinal 60 plate vertically disposed, rigidly attached to said studs, a second stringer disposed thereabove and adjustably attached to said studs, and a longitudinal 65 form plate, vertically disposed, and adjustably attached to said studs, and means for aligning said adjustable form plate with reference to the alignment of said frame.

4. In a form for concrete, a form member including vertically disposed studs, a pair of longitudinally disposed stringers and longitudinally disposed form plates all attached, to one face of said studs, a post-form plate disposed below the 70 upper of said stringers and depending below the other thereof, said plate having an outwardly bent portion underlying said top stringer, and at its lower end an outwardly bent portion overlying the lower of said form plates and means for ad-75

justing the positioning of said post-form plate relatively to said stringers and plates.

5. In a form for concrete, a frame including a plurality of vertically disposed studs, and a plurality of horizontally disposed stiffening members coextensive in length with said form, integrally secured to said studs, a stringer adjustably secured to the face side of said studs, intermediate their height, form plates coextensive in length with said frame, and lying along the face sides of said studs, the lower of said plates being integrally attached to said studs at their lower ends, and the upper of said plates being adjustably attached to the upper end of said studs, and means for adjusting the alignment of said upper plate relative to the alignment of said frame.

6. A form for concrete, including an opposed pair of frames, means for holding said frames apart, and means for tieing same in such position; each of said frames including vertically disposed studs, a longitudinal stringer and a vertically disposed plate extending longitudinally of said frame and rigidly attached to the inner face of said studs, adjacent the lower ends thereof, a second stringer spaced above said first stringer, and adjustably attached to said studs, a second plate extending longitudinally of said frame and adjustably attached to said studs, said plate having its lower edge contacting said stringer, and means for aligning said second plate with reference to the alignment of said frame.

7. A form for concrete, including a pair of form members and means for securing said form members against lateral separation; each of said form members comprising a form, including a plurality of vertically disposed studs, and a plurality of horizontally disposed stiffening members, coextensive in length with said form, rigidly secured to said studs, a stringer adjustably secured to the face side of said studs, intermediate their height, form plates coextensive in length with said frame, and lying along the face sides of said studs, the lower of said plates being rigidly attached to said studs at their lower ends, and the upper of said plates contacting the upper surface of said stringer and being adjustably attached to the upper end of said studs, and means for adjusting the alignment of said upper plate relative to the alignment of said frame.

50 8. A form for concrete, including a pair of form members and means for securing said members against separation; each of said members including vertically disposed studs, a pair of longitudinally disposed, spaced, stringers and longitudinally disposed, spaced, form plates all attached to one face of said studs, a post-form plate disposed below the upper of said stringers

and depending below the other thereof, said plate having at its upper end an outwardly bent portion underlying said top stringer, and at its lower end, an outwardly bent portion overlying the lower of said form plates, means for adjusting the positioning of said post-form plate relatively to said stringers and plates, removable end plates disposed between said post-form plates, said form plates being substantially vertical, and means for adjusting said end plates to 10 vertical position.

9. A form for concrete, including a pair of form members and means for securing said members against separation; each of said members including vertically disposed studs, a pair of longitudinally disposed, spaced, stringers and longitudinally disposed, spaced, form plates all attached to one face of said studs, a post-form plate disposed below the upper of said stringers and depending below the other thereof, said plate having at its upper end an outwardly bent portion underlying said top stringer, and at its lower end, an outwardly bent portion overlying the lower of said form plates, means for adjusting the positioning of said post-form plate relatively to said stringers and plates and removable end plates disposed between said post-form plates, said form plates being substantially vertical.

10. A form for concrete guards for bridges or the like, which guards include upper and lower rails and precast spindles, extending between and incorporated therewith, said form including a pair of form members and means for securing said members against lateral separation; each of said form members having a plurality of vertically disposed studs, horizontally disposed stiffening members coextensive in length with said form, secured to said studs, said members including a pair of angle irons spaced apart each disposed with one leg vertical and lying along the inner faces of said studs and one leg horizontal and extending inward, whereby to contact spindles spaced therebetween, the vertical legs of said angles being slotted, side form plates coextensive in length with said form lying along the inner face of said studs and secured to said studs to accomplish respectively the upper and lower rail side forms; said securing means comprising ties insertable through correspondingly disposed slots of opposite ones of said angles, and means 35 engaging said ties and abutting the outer sides of said angles; and blocks disposable between said spindles extending between the horizontal legs of the upper pair of said angles and supported by said ties, completing the form for the 40 upper of said rails.

LAWRENCE T. THORN.
